UNITED STATES PATENT OFFICE

2,400,628

YARN CONTROL

Arthur N. Cloutier, Lonsdale, R. I., assignor to
Hemphill Company, Central Falls, R. I., a corporation of Massachusetts

Original application April 24, 1939, Serial No.
269,671. Divided and this application January
16, 1945, Serial No. 573,000

4 Claims. (Cl. 66—146)

This application is a division of United States application Serial No. 269,671, filed April 24, 1939, now Patent No. 2,385,611.

This invention relates to new and useful improvements in knitting machines and in particular to yarn take-ups and yarn tensioning devices and the means by which they are controlled. The form of the invention disclosed in the drawings and described herein is adapted for use on the Banner type of circular, independent needle, knitting machine. It should be understood however, that the invention is not limited to this form or to use on this type of knitting machine.

In the drawings:

Fig. 1 is a general view of a circular, independent needle, knitting machine for making split work and showing yarn tensioning devices at both the main and auxiliary sides;

Fig. 2 is an elevation of yarn take-ups, yarn clamps and controlling means;

Fig. 3 is a plan view of the mechanism of Fig. 2;

Fig. 4 is an elevation showing two take-ups and associated mechanisms viewed from the front of the machine;

Fig. 5 is a developed view of the cam drum and cams which control the take-ups;

Fig. 6 is a plan view showing a take-up on the auxiliary side of the machine, auxiliary and main tensions and means for releasing these tensions;

Fig. 7 is an elevation of the mechanisms of Fig. 2 insofar as it relates to the auxiliary tension;

Fig. 8 illustrates the cams and linkage by means of which the take-up control is operated; and

Fig. 9 is a plan view, partly in section, of the mechanisms of Fig. 8.

The yarn take-ups, two of which are shown in Figs. 1 and 2 are mounted as usual upon the upper part of the machine. Each take-up consists of an arm 1, one end of which terminates in an eyelet 2 and the other end of which is mounted in a block 3 behind shaft 4 and a hooked adjusting rod 6 slidably mounted in plate 7 and which can be fastened in any position by screw 8 by means of which the tension of spring 5 can be regulated.

Pivoted as at 9 on an extension of bracket 10 is a yarn clamp in the form of a downwardly depending arm 11 and a plate 12 so positioned that the lower end of arm 11 will rest upon it when the arm is inclined somewhat to the rear of its vertical position as shown in Fig. 2.

The front end of arm 11 adjacent its lower edge is provided with a notch 13. Pivoted block 3 extends rearwardly of shaft 4 so that its upper

edge 14 will engage notch 13 when the take-up swings down with the result that arm 11 will be swung backward and its lower end moved out of contact with plate 12. This should occur somewhat before the take-up has reached its lowest position.

The operation of this device will be evident to those skilled in the art. A yarn 15 from a cone of yarn is fed through a suitably positioned eyelet 16 between the lower end of arm 11 and plate 12, through another eyelet 17, eyelet 2 at the end of take-up arm 1, eyelet 18 and so on to the yarn lever by means of which it is fed to the needles. Whenever any slack of yarn 15 occurs on the needle side of the take-up arm 1 will rise to the extent permitted by the slack. If this rise is sufficient, arm 11 will engage with plate 12 and yarn 15 will be clamped therebetween, as shown in Fig. 2, so that no more yarn can feed from the cone for the time being. Thus the full capacity of the take-up is reserved for taking up any slack in the yarn at the needle side of the take-up and is not reduced by the undesired feeding of additional yarn from the cone at such time. Whenever the tension upon yarn 15 on the needle side of the take-up becomes great enough to swing arm 1 downward sufficiently to cause edge 14 of block 3 to disengage arm 11 from plate 12 the yarn is released from the clamp so that it is free to feed from the cone in accordance with the knitting requirements.

Whenever the knitting of the yarn controlled by the take-up is discontinued, the operation of the take-up should also be stopped otherwise the yarn may be pulled out of the binder. This is accomplished by means shown in Figs. 2-5 which consists of drum 19 horizontally mounted on a shaft 20 supported by a suitable bracket below the pivoted end of the take-up as shown in Figs. 2 and 4. The surface of drum 19 is provided with one or more cams 21 (Figs. 3, 4 and 5) engageable with the lower end of a rocker 22 pivoted at 23 on bracket 10 and having an offset upper end 24 engageable with the edge 25 of semi-circular extension 26 of the pivoted block 3 by which take-up arm 1 is supported. The lower end of rocker 22 is normally maintained against drum 19 by a spring 27. Whenever a cam 21 on drum 19 engages the lower end of rocker 22 it will be swung away from the drum with the result that upper end 24 of rocker 22 will be moved out of engagement with edge 25 of block 3 thus releasing the take-up. Whenever rocker 22 is not riding upon a cam 21 its end 24 will engage with end 25 and will prevent the take-up from operating. By

suitably positioning cams 21 this action may be brought about at any desired time or times.

Drum 19 is provided with a ratchet 28 by means of which it is turned through a pawl 29. Pawl 29 is mounted on plate 30 swingable upon the drum shaft 26. Pawl 29 is operated by a lever 31 connected to one end of lever 32, the other end of which is maintained in engagement with a pattern drum 33 (Figs. 8 and 9). In this way, the rotation of drum 19 is controlled as desired and by this means and by the positioning of cams 21 on drum 19 the operation of the take-up is arrested or permitted.

The functioning of the take-up is further assisted by correspondingly controlling the yarn tensioning device on the needle side of the take-up. In Figs. 1, 2 and 3 yarn tensions are shown at 34 and 35 for yarns being fed at the main and auxiliary sides of the machine, respectively. Whenever the machine is knitting the corresponding tension must, of course, be in operation but when this knitting is discontinued and a take-up is functioning to take up slack in a yarn the corresponding yarn tension should be open so as to offer no opposition to the action of the take-up.

The tensions shown are of a common form, which will be recognized by those skilled in the art, consisting of two discs between which the yarn passes and which are pressed together by a spring, the tension of which can be adjusted to secure the desired yarn tension. Means for automatically opening or releasing a yarn tension of this type without disturbing its operative adjustment is shown in Figs. 1, 6 and 7. Directly in line with main yarn tension 34 is a pivoted arm 36 having a wedge shaped edge 37 so positioned that when this end of arm 36 is rocked downwardly wedge shaped edge 37 will enter between the two discs of tension 34 and separate them so that the tension on the yarn is released. This tension release is operated from any suitable timing mechanism through suitable connections indicated in Figs. 1 and 6 as rod 38.

A somewhat different form of tension release is shown in Figs. 1, 6 and 7 for auxiliary yarn tension 35. This consists of a blade 39 having a wedge shaped end 40 adapted to enter between the two discs of tension 35. The other end of blade 39 projects inwardly into the path of a cam 41 mounted upon the gear 42 through which the dial is rotated or upon any other suitable rotatable part. Blade 39 is slidably mounted upon a bracket 43 so that it can be moved radially by cam 41. Whenever blade 39 is riding upon cam 41 its wedge shaped end 40 will be forced between the discs of tension 35 thus separating them and eliminating the tension upon the auxiliary yarn. When blade 39 is not in contact with cam 41 its position remains unchanged, because of the fric-

tion between it and bracket 43 provided by spring 44, until cam 41 engages it to draw it inwardly and out of contact with tension 35 which is then automatically restored to operating condition.

5 The type of tension release last described is obviously suitable only for reciprocatory knitting.

Another control is provided for tension 35 by means of which it can be held open for any desired length of time regardless of the continued 10 operation of blade 39 by its operating cams. This consist of a pin 46 (Figs. 1 and 6) so mounted 15 upon a rocker 47 that it can be made to engage the edge of one of the discs of tension 35 to tilt this disc in relation to the other and thus release the tension on the yarn. Rocker 47 may be operated by any suitable timing mechanism such as that shown in Fig. 1 which consists of a rod 48, connected to the arm which controls the 20 auxiliary yarn feeding lever. Whenever the yarn feeding lever is in yarn feeding position tension 35 will also be in operating position. Whenever the yarn feeding lever is raised, pin 46 will engage tension 35 to open it, as already described.

I claim:

25 1. In a split knitting machine a yarn take-up adapted to take up yarn slack during reciprocatory knitting whenever yarn is not under tension at the needles, a yarn tension, resilient means for maintaining said tension in operating condition and means for releasing said tension whenever said take-up is taking up yarn slack, said tension releasing means being operated by a horizontally disposed cam.

30 2. A knitting machine according to claim 1 35 which also includes a second means for releasing the yarn tension at any desired time without affecting the operation of said other tension releasing means.

35 3. In a split knitting machine a yarn take-up 40 adapted to take up yarn slack during reciprocatory knitting whenever yarn is not under tension at the needles, a yarn tension, resilient means for maintaining said tension in operating condition and means for releasing said tension whenever said take-up is taking up yarn slack, said tension releasing means being directly engaged with a horizontally disposed operating cam.

45 4. In a split knitting machine having a reciprocable cylinder, a yarn take-up adapted to take up yarn slack during reciprocatory knitting whenever yarn is not under tension at the needles, a yarn tension, resilient means for maintaining said tension in operating condition and means for releasing said tension whenever said take-up is taking up yarn slack, said tension releasing means being operated by a horizontally disposed cam and said cam being reciprocable with said cylinder.

ARTHUR N. CLOUTIER.
